Patented Mar. 15, 1921.

UNITED STATES PATENT OFFICE

JAMES C. DAWSON, OF WEBSTER GROVES, MISSOURI.

BOOKBINDING.

1,371,739.

Specification of Letters Patent.

Patented Mar. 15, 1921.

Application filed January 17, 1920. Serial No. 352,074.

To all whom it may concern:

Be it known that I, JAMES C. DAWSON, a citizen of the United States, and resident of Webster Groves, county of St. Louis, and 5 State of Missouri, have invented certain new and useful Improvements in Bookbinding, of which the following is a specification, and which are illustrated in the accompanying drawings, forming a part thereof.

10 The invention relates to the art of book binding, and has for its object to provide improved means for closing the back of a volume which has been formed by securing a stack of loose sheets between a pair of 15 separate covers.

In the accompanying drawings,

Figure 1 is a detail perspective view showing a bound volume embodying the features of improvement provided by the invention; 20 Fig. 2 is a sectional view taken on plane indicated by the line 2—2 of Fig. 1;

Fig. 3 is a perspective view showing the part employed for closing the back of the volume; and

25 Fig. 4 is a detail perspective of a modification.

When records are kept upon loose sheets, held in a file or the like, a subsequent preservation of the sheets for future reference 30 is frequently required. For this purpose a quantity of the sheets, as 10, may be secured between separate covers 11, 12. If only occasional reference to the sheets 10 is anticipated, it is desirable that both the covers 35 11, 12, and the means employed for securing the sheets between them, should be of the most inexpensive character. On the other hand, the rigidity of the volume of sheets, and the convenience with which it 40 may be withdrawn from its place between a number of similar volumes, are greatly improved if the volume is provided with a stout back piece, as 13. Furthermore, the provision of such a back piece affords a place 45 for indicating the character of the contained records in a place where this writing may be examined without handling the volume.

As shown, each of the covers 11, 12, takes the form of a flat cloth-covered board 50 formed with a hinge 14 extending transversely across the same near one end, to permit opening the volume when the covers are firmly secured upon the sheets. The binding may take any convenient form, that 55 illustrated being a staple 15, having clenched ends 16. In order that both the cross-piece,

as 17, and the clenched ends 16 of the staple 15 may be flush with the corresponding cover 11, 12, each cover is preferably equipped with a sheet metal washer 18, having a countersunk portion 19 for receiving the corresponding part of the staple, all in the manner more fully disclosed in my patent application on book binding, Case D, Ser. No. 351,073 filed concurrently herewith. 60

For attaching the back piece 13, each cover 11, 12, is supplied with a gummed flap 20. One portion of this flap is permanently glued to the cover adjacent its inner end, and preferably extends under the corresponding washer 18, another portion, 21, of the flap being originally free. Each flap extends throughout the width of the cover and is gummed over its entire initially upper surface. In the original condition of 75 the covers 11, 12, the free portion 21 of each flap 20 lies flat against the corresponding cover in front of the hinge line 14.

As the length of the back piece 13 will be determined by the thickness of the volume, 80 this piece is conveniently supplied in strip form equal in width with the covers 11, 12, but intended to be cut to length after the sheets 10 and covers 11, 12, have been assembled. To facilitate the cutting, the strip 85 is ruled with parallel transverse lines 22 upon the inside. In applying the back piece 13 the gummed upper surface of one of the flaps 20 is moistened, and an end portion of the back piece is applied thereto, to 90 extend inwardly from the rear edge of the cover over the secured portion of the flap, or approximately to the hinge line 14. The free portion 21 of the flap is then folded over upon the end of the back piece, and the 95 operation is repeated at the other side of the volume and with the other end of the back piece, care being taken that the back piece is of such length that it may be stretched taut across the end of the volume. 100

While the back piece 13 and flaps 20 will be desirably made from a stiff grade of stout paper, provision is preferably made to resist tearing the back piece when this part is grasped for the purpose of withdrawing the 105 volume from its place between similar volumes on a shelf or the like (not shown.) For this purpose the back piece is preferably formed with a stitched hem 23 along each margin. The back piece 13 not only protects 110 the inner ends of the sheets 10 and provides a labeling surface, but it also serves to

greatly strengthen the finished volume. Furthermore, it is readily applied, imparts a finished appearance to the volume, and the manner of its application contributes to its 5 strengthening effect.

A modification is shown in Fig. 4, in which an end of the back strip 13 is permanently secured to back cover 12, its length loosely extended inwardly along the surface of the 10 cover. Preferably the strip is pasted against the portion beyond the hinge, and the metal washer 18 is placed over the secured portion of the strip. In the binding of the book the strip is folded on itself at 15 about the hinge line, as shown in Fig. 4, and being carried around the back of the book, its end is fastened by means of gummed strip 20, 21, as in the modification first described.

20 I claim as my invention:

1. A book comprising, in combination, a stack of sheets, separate covers, fastening means uniting the sheets and covers, a flap extending transversely across each cover 25 and permanently secured against the outer face of the cover over an area extending inwardly from the rear edge of the cover a distance equal to half the width of the flap, and a strip covering the rear end of the stack of 30 sheets, a portion adjacent each end of the strip being extended over and secured against that part of one of the flaps which is secured against the corresponding cover, the other part of each flap being folded over 35 upon and secured against the adjacent end portion of the strip.

2. In a book binding, in combination, a

pair of separate covers, and a flap extending transversely across each cover and permanently secured against the outer face of the 40 cover over an area extending inwardly from the rear edge of the cover a distance equal to half the width of the flap, the remainder of the flap being free and the entire upper surface of the flap being gummed. 45

3. In a book binding, in combination, a pair of separate covers each having a transverse hinge adjacent its rear edge, and a gummed transverse flap springing from each 50 cover upon the outside of the same in rear of but immediately adjacent the corresponding hinge, the gummed surface of the flap facing the rear edge of the cover.

4. In a book binding, in combination, a pair of separate covers each being punched 55 adjacent its rear edge for the reception of a binding staple or the like, and a gummed transverse flap springing from each cover upon the outside of the same in front of the said punching, the gummed surface of the 60 flap facing the rear edge of the cover.

5. In a book binding, in combination, a back cover, a strip secured to the cover for a short distance inwardly from the back 65 end, and adapted to be folded on itself and carried around and to cover the back of the book, a front cover having a gummed flap one-half of the flap secured to the outside of the rear end of the cover, whereby the strip may have its end pasted to the secured portion of the flap and the flap may be folded over and pasted to the pasted end of the strip. 70

JAMES C. DAWSON.
